UNITED STATES PATENT OFFICE.

ALBERT H. WHITMORE, OF BROOKLYN, NEW YORK, ASSIGNOR TO TITUS BLATTER & COMPANY, OF NEW YORK, N. Y., A CORPORATION OF NEW YORK.

ARTIFICIAL LEATHER AND METHOD OF MANUFACTURING THE SAME.

1,244,567.

Specification of Letters Patent. Patented Oct. 30, 1917.

Application filed July 7, 1917. Serial No. 179,230.

To all whom it may concern:

Be it known that I, ALBERT H. WHITMORE, a citizen of the United States, residing at Brooklyn, in the county of Kings and 5 State of New York, have invented certain new and useful Improvements in Artificial Leather and Methods of Manufacturing the Same; and I do hereby declare the following to be a full, clear, and exact description of the invention, such as will enable others skilled in the art to which it appertains to make and use the same.

This invention relates to the production of artificial or imitation leather, and 10 15 20 25 30 35 40 45 50 55 60 65 70 75 80 85 90 95 100 105 110

templates in addition to the material produced the method of making such material. Numerous attempts have been made to produce a substitute for leather which will be free from objectionable odors, and at the same time possess the necessary characteristics of pliability, softness, strength, tenacity, durability, and the appearance of leather.

In the manufacture of artificial leather upon a fabric base, heretofore, the principal ingredients used have been castor oil and pyroxylin. From time to time various attempts have been made to modify the use of these ingredients by combining them with others in an effort to produce a commercially successful material, which was free from disagreeable odors, and which also possessed the characteristics of leather. These attempts have shown that use of a large percentage of castor oil results in a product which readily cracks, allowing its surface to peel and scrape off, and a product also commercially unsatisfactory because of a most disagreeable odor.

It is an object of the present invention not only to overcome the aforesaid difficulties and objections, but at the same time to produce a leather substitute possessing among other good qualities the following characteristics of genuine leather, namely: permanent pliability, strength, tenacity, softness and durability under varying atmospheric or climatic conditions.

A further object is the production of a leather substitute which is reversible and equally serviceable upon either or both sides, as also upon any of its edges which will not ravel or fray out with use.

A further object is the production of a leather substitute which lends itself pe-

culiarly to the action of embossing rolls or dies, in exact imitation of various hides or skins, and presents an exceptionally good appearance both when embossed or finished smooth.

In practice, I use palm oil to obtain the above results. This, together with castor oil and nitro-cellulose or pyroxylin forms the composition with which the base fabric is treated. Other ingredients, such as wood alcohol, amyl acetate, refined fusel oil, benzene, and coloring pigments are also used.

It is also an object of the present invention to produce artificial or imitation leather, or a leather substitute by subjecting its base fabric to a dipping or submerging operation, as distinguished from a mere surface treatment or coating, whereby the individual threads are treated upon all sides, and the fabric thoroughly impregnated with my solution containing, in addition to the pyroxylin product, palm oil and castor oil, preferably in equal parts, after which a finishing coat of substantially pure nitro-cellulose is applied in solution.

This product may then be perforated for the purpose of affording it the breathing properties of leather, at the same time increasing its pliability and permitting the composition to become more firmly embedded in the fabric.

In correct imitation of various hides and skins the aforesaid product may then be embossed by agency of suitable rolls or dies, thus practically obscuring from view the perforations aforesaid, and rendering the product moisture proof without in the least destroying its breathing properties; that is to say, my improved compound is by pressure actually driven or forced into the said perforations, as also into the meshes of the fabric itself, thus further interlocking the whole, and thereby effectually preventing the passage of moisture without actually closing the perforations.

Reference being had to the drawings which form part of this application for Letters Patent, and which illustrate the method steps by which my improved substitute for leather may be produced.

Figure 1 shows diagrammatically the first step or dipping operation to which the fabric base is subjected for the purpose of thoroughly impregnating it with my solution containing palm oil and castor oil.

Fig. 2 illustrates diagrammatically the same fabric after it has received its first coating of my solution containing palm oil and castor oil upon both sides thereof, the proportion of said oils exceeding the pyroxylin ingredients.

Fig. 3 is a view similar to Fig. 2 showing subsequent and additional coatings of the fabric.

Fig. 4 is a view similar to Fig. 3, but including upon both sides a finishing coat or layer of nitro-cellulose, which may contain slight quantities of the oils.

Fig. 5 shows diagrammatically a fragment of the product perforated at frequent intervals.

Fig. 6 illustrates in plan a fragment of the finished product, the same having been finally passed through embossing rolls or dies to give it appropriate surface ornamentation, and more effectually bond the several elements together, and,

Fig. 7 is a detail diagrammatic and relatively enlarged view of a portion of the completed product, wherein the surface has been suitably embossed, and its breathing perforations practically obscured from view by the process of embossing.

Generally stated, the invention includes a base material preferably of fabric 1 having a suitable mesh of warp and weft threads designed and adapted to be thoroughly impregnated by a pyroxylin solution together with palm oil and castor oil, and to receive a finishing coat of substantially pure nitro-cellulose. The solution containing palm oil and castor oil is applied to the fabric by a dipping process whereby it is allowed to saturate the threads upon all sides and firmly embed itself within the meshes of the woven material. The mixture containing palm oil and castor oil is preferably thin, and as many saturating or impregnating operations may be employed as desired.

I have found that when the palm oil and castor oil are equally proportioned and applied through several dipping operations in a thin solution the best results are obtained.

In the drawings I have illustrated for example four coatings of my solution containing palm oil and castor oil applied to the fabric in succession. In practice, the first coating indicated at 2 upon both sides of the fabric is applied very thin, thereby permitting a free saturation thereof. The subsequent coatings of the solution containing palm oil and castor oil indicated at 3 may be thicker and as numerous as desired.

A finishing coat 4 of substantially pure nitro-cellulose is then applied, preferably by dipping, the result being a product of pliable, soft and tenacious quality, having an edge which is highly advantageous for sewing and joining purposes. The thorough impregnation and saturation of the

fabric together with the properties of the palm oil gives the product an edge which can be easily trimmed and worked without raveling or fraying out.

The perforations of the product shown at 5 in Figs. 5 and 7 tend to soften and render it more pliable and at the same time afford it the breathing qualities common to genuine leather. This characteristic is highly advantageous in the manufacture of boots, shoes and other articles of wearing apparel usually made from hides and skins.

During the embossing operation the perforations 5 are practically obliterated from view by action of the rolls or dies which force the various coatings aforesaid into the said perforations, thereby more effectually interlocking and securing the several elements together. This operation has been found to work readily with the combining of castor oil and palm oil in solution and to give greater strength to the bond between the base of the fabric and the final coatings as shown in Fig. 7. The perforations, by the embossing operation, are closed sufficiently to prevent the passage of moisture, but not to interfere with the circulation of air therethrough.

In the production of a leather substitute made in accordance with my invention the advantages of the use of palm oil and castor oil in equal parts, are numerous. For example, the drying out of the product is less likely to occur and is certainly deferred for a considerable period; the imitation of various hides and skins by the embossing operation is effected to greater advantage and without danger of its subsequent cracking; and the elimination of the odor of castor oil is rendered possible by its reduced proportion.

In the practice of the invention it will be readily understood that various ingredients which will give the odor of different leather, may be added without affecting the quality or use of the product.

What I claim is:

1. A fabric impregnated with a composition containing castor oil, palm oil and nitro-cellulose.

2. The process which consists in impregnating fabric with a composition containing castor oil and palm oil, then coating in a solution of nitro-cellulose and then embossing the surface of the fabric.

3. The process which consists in impregnating fabric with a composition containing castor oil and palm oil in equal parts, then coating in a solution of pure nitro-cellulose, and then embossing the surface of the fabric.

4. The process which consists in impregnating fabric with a composition containing castor oil and palm oil, then coating with a solution of nitro-cellulose, then perforat-

ing the fabric and then embossing the fabric.

5. The process which consists in impregnating fabric with a composition containing palm oil, coating with a solution of nitro-cellulose, then perforating the fabric and then embossing the fabric.

6. The process which consists in impregnating by dipping fabric into a composition containing palm oil, coating with a solution of nitro-cellulose then perforating the fabric, and then embossing the fabric to obscure the perforations.

7. The process which consists in impreg-

nating by dipping a cross threaded woven fabric into a composition containing palm oil and castor oil, then coating the fabric with pure nitro-cellulose, then perforating the fabric and finally embossing the fabric to conceal the perforations.

20

In testimony whereof I affix my signature, in presence of two subscribing witnesses.

ALBERT H. WHITMORE.
